(57) **CLAIM**

The ornamental design for a lure enclosure, as shown and described.

DESCRIPTION

FIG. 1 is a right front perspective view of the preferred embodiment of a lure enclosure in a closed form.

FIG. 2 is a left rear perspective view thereof.

FIG. 3 is a front view thereof.

FIG. 4 is a rear view thereof.

FIG. 5 is a right view thereof.

FIG. 6 is a left view thereof.

FIG. 7 is a top plan view thereof.

FIG. 8 is a bottom plan view thereof.

FIG. 9 is a right front perspective view of the preferred embodiment of a lure enclosure in an open form.

FIG. 10 is a right rear perspective view thereof.

FIG. 11 is a right view thereof.

FIG. 12 is a left view thereof.

FIG. 13 is a rear view thereof.

FIG. 14 is a front view thereof.

FIG. 15 is a top plan view thereof; and,

FIG. 16 is a bottom plan view thereof.

The broken lines showing a fishing rod are for the purpose of illustrating the environmental structure and form no part of the claimed design.
